US00D997664S

(12) **United States Design Patent** (10) **Patent No.:** **US D997,664 S**
(45) **Date of Patent:** **** Sep. 5, 2023**

(54) **HEAD OF GARDENING TOOL**

(71) Applicant: **CIXI HUAZHIJIE PLASTIC PRODUCT CO., LTD.**, Zhejiang (CN)

(72) Inventors: **Jie Hua**, Zhejiang (CN); **Shimin Hua**, Zhejiang (CN)

(73) Assignee: **CIXI HUAZHIJIE PLASTIC PRODUCT CO., LTD.**, Zhejiang (CN)

(**) Term: **15 Years**

(21) Appl. No.: **29/794,216**

(22) Filed: **Jun. 10, 2021**

(30) **Foreign Application Priority Data**

Apr. 12, 2021 (CN) 202130202641.6

(51) **LOC (14) Cl.** **08-05**

(52) **U.S. Cl.**

USPC **D8/13**

(57) **CLAIM**

The ornamental design for a head of gardening tool, as shown and described.

DESCRIPTION

FIG. 1 is a first perspective view of a head of gardening tool showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second perspective view thereof showing the head of gardening tool attached to a handle in a first use state; and,

FIG. 9 is a third perspective view thereof showing the head of gardening tool attached to a handle in a second use state. The broken lines are included for the purpose of illustrating portions of the head of gardening tool and form no part of the claimed design. The broken line handle shown in FIGS. 8 and 9 is included for the purpose of illustrating environmental structure that forms no part of the claimed design.

1 Claim, 7 Drawing Sheets
